UNITED STATES PATENT OFFICE.

SAMUEL COHN, OF NEW YORK, N. Y.

DESIGN FOR A LABEL-BLANK.

40,263.

Specification for Design. Patented Sept. 14, 1909.

Application filed July 9, 1909. Serial No. 506,860. Term of patent 7 years.

To all whom it may concern:

Be it known that I, SAMUEL COHN, a citizen of the United States, residing at the city of New York, borough of Manhattan, in the county and State of New York, have invented a new, original, and ornamental Design for a Label-Blank, of which the following is a specification, reference being had to the accompanying drawing, forming part thereof, in which is shown a face view of a label-blank incorporating my said design.

In said drawing the label blank is shown as a rectangular outline having rounded corners, and a ribbed border. Near the center of the label blank is horizontally arranged a longitudinal band or scroll having its ends curled and at one end of said band or scroll is shown a seal suspended from a ribbon.

At about the center of the label blank and above said scroll or band is displayed a shield having an elliptical panel bearing a crown; two eagle heads, and a support below said heads. From the opposite lower edges of the shield extend conventionalized branches upon which are arranged a deer and a hound serving as supporters for the shield.

At the upper corners of the label are disposed curved or crescent shaped ornaments of conventionalized foliage.

I claim—

The ornamental design for a label blank, as herein shown and described.

SAMUEL COHN.
